THERMOSTATICALLY CONTROLLED PUMP
John P. Stefan, Birmingham, Mich., assignor to Ford Motor Company, Dearborn, Mich., a corporation of Delaware

Filed Nov. 13, 1964, Ser. No. 411,016
20 Claims. (Cl. 123—41.02)

This invention relates to a thermostatically controlled fluid circulating device and more particularly to a thermostatically controlled coolant pump or an internal combustion engine.

In many instances it is necessary to circulate a fluid by means of a pump or other fluid circulating device that is responsive to temperature. The pump or fluid circulating device may operate in response to the temperature of the fluid circulated or to some other temperature. It heretofore has been the practice to employ some element that has thermal characteristics for controlling the operation of the fluid circulating device. Bimetallic springs, metals having high coefficients of thermal expansion and wax pellets are well known forms of thermally responsive elements that are used for this purpose. When thermally responsive elements of this type are used, they must be in thermal contact with the part whose temperature is being sensed. Frequently, spacial limitations and other factors make this thermal contact either impossible or difficult.

It is a principal object of this invention to provide a fluid circulating device that is temperature responsive without requiring the use of an element having thermally responsive properties.

In liquid cooled internal combustion engines it is the general practice to provide a coolant pump for circulating the liquid coolant throughout the cooling jacket of the engine and through a radiator that dissipates the heat generated by the engine. The coolant pump must have sufficient size to meet the maximum cooling requirements of the engine. If the pump is designed to meet the maximum cooling requirements of the engine, it will require significant power to operate the pump at partial and full loads. The coolant pump, therefore, may consume considerable power for its operation during times when its full capacity is not needed.

It is a further object of this invention to provide a temperature responsive cooling pump for an internal combustion engine.

A temperature responsive means for actuating a fluid pump embodying this invention comprises a venturi section. Means is provided to circulate a fluid through the venturi section. The fluid circulated through the venturi section is adapted to vaporize at the throat of the venturi section at a predetermined temperature. A device is provided to generate a signal when the fluid vaporizes within the throat and means are provided to drive the pump in response to the signal of the device.

A coolant pump for an internal combustion engine embodying this invention comprises a first engine driven coolant pump that circulates coolant through the cooling jacket and radiator of the engine at all times. A second coolant pump is provided. A thermally responsive device is provided for actuating and driving the second coolant pump from the engine only at times when the coolant temperature exceeds a predetermined temperature. In a preferred embodiment of the invention, the temperature sensing device for actuating the second coolant pump may be of the type described in the preceding paragraph.

Further objects and advantages of this invention will become more apparent as this description proceeds, particularly when considered in conjunction with the accompanying drawings, wherein:

2

FIGURE 1 is a partial perspective view, with portions broken away, of a liquid cooled internal combustion engine embodying this invention.

FIGURE 2 is a cross-sectional view taken substantially along the center line of the coolant pump shown in FIGURE 1.

Referring now in detail to the drawings and in particular to FIGURE 1, a liquid cooled internal combustion engine is indicated generally by the reference numeral 11. The cylinder block and cylinder heads of the engine 11 are provided with a cooling jacket through which a liquid coolant is circulated by means of a coolant pump, indicated generally by the reference numeral 12 and shown in more detail in FIGURE 2. The actual construction of the cooling jacket per se does not form a part of this invention and will not be described in detail. The heat generated by the operation of the engine is dissipated to the atmosphere from a cross flow radiator, indicated generally by the reference numeral 13. The radiator 13 has a core 14 and header tanks 15 and 16 positioned at each side of the core 14.

The coolant pump 12 has an outer housing 17 that terminates in each side in branch arms 18 and 19 that are affixed to the front of the engine 11. The branch arms provide coolant outlets for delivering coolant to the cooling jacket of the engine 11 from the coolant pump 12. The outer housing 17 also has an inlet fitting 21 that is formed with a coolant inlet passage. The inlet fitting 21 is connected to one end of a flexible hose 22 which is connected, in turn, to the lower end of the radiator header tank 16 so that coolant which has passed through the radiator 13 may be received by the coolant pump 12.

After the coolant has been circulated through the cooling jacket of the engine, it may be discharged through an outlet fitting 23 that is supported at the front of the engine. The outlet fitting 23 is in communication with the lower side of an expansion tank 24. A flexible hose 25 interconnects the expansion tank 24 with the upper end of the header tank 15. A filler cap 26 is provided at the top of the expansion tank 24 to permit the cooling system to be filled. A thermostatic valve (not shown) may be provided in the outlet fitting 23 or at any other suitable location for controlling the flow of coolant through the radiator 13 in response to the coolant temperature.

A driving shaft 27 for the coolant pump 12 is journaled in the front of the housing 17 by bearings 28 (FIGURE 2). A pulley 29 is affixed to the forward end of the driving shaft 27 and a pulley 31 is affixed to the forward end of the engine crankshaft 32. A belt 33 is provided to transmit rotary motion from the crankshaft pulley 31 to the water pump pulley 29.

Referring now in detail to FIGURE 2, the water pump housing 17 forms a forward, annular coolant inlet cavity 34 that is interconnected with a rearward pumping cavity 35. The pumping cavity 35 is enclosed by a cover plate 36 that is affixed to the housing 17 by a plurality of bolts 37. An inner impeller 38 is affixed to the inner end of the driving shaft 27, as by a key 39. A seal 41 is positioned around the periphery of the driving shaft 27 at one side of the inlet cavity 34 to preclude the leakage of coolant from the coolant pump 12. An outer impeller 42 has a pilot portion 43 that is journaled within a bore 44 of the inner impeller 38. The impellers 38 and 42 are coaxially disposed and axially aligned within the pump cavity 35.

When one or both of the impellers 38 and 42 are being driven by rotation of the engine crankshaft 32, coolant will be discharged through the branch arms 18 and 19 into the engine cooling jacket. If the thermostatic valve is open, the coolant will be discharged from the engine

cooling jacket into the radiator 13 and returned to the inlet side of the coolant pump 12 through the inlet fitting 21. If the thermostatic valve is closed, coolant will still be circulated through the cooling jacket of the engine. In this instance the coolant is returned to the inlet side of the coolant pump 12 from a bypass outlet 45 formed at the front of the engine 11. The bypass outlet 45 is axially aligned with a venturi section 46 that is formed within a tube that is fixed within a bore 47 formed in the coolant pump housing 17. The bore 47 opens into the inlet cavity 34. A flexible hose 48 interconnects the venturi section 46 with the bypass outlet 45.

It should be apparent that the inner impeller 38 will be driven continuously when the engine is operating. The outer impeller 42, because it is journaled relative to the inner impeller 38 and the driving shaft 27, will idle and not circulate coolant under normal conditions. The inner impeller 38 is made of sufficient size so that it will satisfy the normal cooling requirements of the engine 11. In the event that an abnormal cooling load is encountered, driving means are provided for actuating the outer impeller 42 so that it will rotate in unison with the inner impeller 38. The driving means includes a thermally responsive clutch, now to be described.

A frictional clutch surface 49 is affixed to the rear face of the inner impeller 38 adjacent to a corresponding clutch surface 51 of the outer impeller 42. Normally there will be a small axial gap between the clutch faces 49 and 51. The pilot portion 43 may slide axially within the bore 44 so that the clutch surfaces 49 and 51 may move into and out of engagement. A diaphragm 52 extends across the rear face of the pumping cavity 35 to define a pressure chamber 53 between the rear surface of the diaphragm 52 and the front surface of the cover plate 36. The diaphragm 52 has a substantially rigid disc 54 affixed at its center upon the axis of the impellers 38 and 42. A steel ball 55 is received in a socket 56 formed in the rear face of the outer impeller 42 and a socket 57 formed in the front face of the disc 54. A Belleville spring 58 engages the cover 36 and the plate 54 to exert an axial force in a forward direction upon the outer impeller 42 through the ball 55. This force tends to cause the clutch faces 49 and 51 to move into engagement.

The pressure within the chamber 53 is varied in response to a change in the temperature of the engine coolant so that the engagement of the clutch faces 49 and 51 will be dependent upon the coolant temperature. This is accomplished by providing a fitting 59 at the center of the cover plate 36 that permits fluid communication between the cavity 53 and the venturi section 46 at its throat 61. A flexible hose 62 extends from the fitting 59 to a nipple 63 formed integrally with the venturi section 46. A fluid passage 64 extends through the nipple 63 and terminates at the venturi section throat 61.

The temperature responsive coolant pump operates in the following manner. When the engine is operating and the coolant temperature is low, the rotating driving shaft 27 will cause the impeller 38 to rotate and circulate coolant through the cooling jacket of the engine 11. The coolant that is returned to the inlet side of the coolant pump through the venturi section 46 will flow at a relatively high velocity through the throat 61. This high velocity flow will cause a decreased pressure at the throat 61 which is transmitted through the passage 64, hose 62 and fitting 59 to the chamber 53. The resulting pressure differential on the opposite sides of the diaphragm 52 overcomes the force in the Belleville spring 58 and permits the clutch faces 49 and 51 to separate axially. The outer impeller 42 will then idle with respect to the inner impeller 38.

As the coolant temperature rises, it will eventually reach a point at which it will vaporize or cavitate at the throat 61. When the coolant turns to a vapor at the throat 61, the pressure will increase or the vacuum will decrease.

The decreased vacuum that is transmitted to the cavity 53 will no longer be sufficient to overcome the action of the Belleville spring 58 and an axial pressure will be exerted upon the outer impeller 42 through the ball 55. This axial pressure will cause the clutch faces 49 and 51 to move into engagement and the impellers 38 and 42 will rotate in unison. When the impellers 38 and 42 rotate in unison the capacity of the coolant pump 12 increases and additional coolant will be circulated through the cooling jacket of the engine 11 and through the radiator 13 if the thermostatic valve is open.

The increased flow of coolant will continue until its temperature falls below the point at which it will vaporize at the throat 61 of the venturi section 46. When this occurs, the clutch again will become disengaged and only the inner impeller 38 will circulate coolant.

Although it is desirable to operate the engine 11 at as high a temperature as practical, its operating temperature will depend upon the boiling point of the liquid coolant that is used. In a like manner, the temperature at which it is desirable to drive the outer impeller 42 will depend upon the boiling point. It should be apparent that the actual temperature at which the clutch faces 49 and 51 are engaged will depend upon the characteristics of the venturi section 46 and the characteristics of the fluid coolant. If the venturi section 46 is designed for a given coolant and a coolant having a higher or lower boiling point is substituted, the thermal operation of the outer impeller 42 will automatically compensate for the change in the coolant boiling point. If a coolant having a lower boiling point is used, it will flash sooner at the venturi throat 61 causing the outer impeller 42 to commence to be driven at a lower temperature. In a like manner, if a coolant having a higher boiling point is used, it will flash later at the throat 61 and the outer impeller 42 will commence to be driven at a higher temperature.

It is to be understood that this invention is not limited to the exact construction shown and described, but that various changes and modifications may be made without departing from the spirit and scope of the invention, as defined by the appended claims.

I claim:

1. Temperature responsive means for actuating a fluid circulating means comprising a venturi section, means for circulating a fluid through said venturi section, the fluid circulated through said venturi section being adapted to vaporize at the throat of said venturi section at a predetermined temperature, means for generating a signal when the fluid vaporizes within said throat, and means for driving said fluid circulating means in response to the signal of said last-named means.

2. A fluid system comprising a first fluid circulating means adapted to circulate a fluid in response to temperature variations and means for actuating said first fluid circulating means comprising a venturi section, a second fluid circulating means for circulating a fluid through said venturi section, the fluid circulated through said venturi section being adapted to vaporize at the throat of said venturi section at a predetermined temperature, means for generating a signal when the fluid vaporizes within said throat, and means for driving said first fluid circulating means in response to the signal of said last-named means.

3. Temperature responsive means for actuating a fluid circulating means comprising a venturi section, means for circulating a fluid through said venturi section, the fluid circulated through said venturi section being adapted to vaporize at the throat of said venturi section at a predetermined temperature, means for sensing the pressure at said throat for generating a signal when the fluid vaporizes within said throat, and means including pressure responsive means for driving said fluid circulating means in response to the signal of said last-named means.

4. A fluid circulating system comprising first fluid circulating means adapted to be operated in response to

temperature variations and means for actuating said first fluid circulating means comprising a venturi section, a second fluid circulating means for circulating a fluid through said venturi section, the fluid circulated through said venturi section being adapted to vaporize at the throat of said venturi section at a predetermined temperature, means for sensing the pressure at said throat for generating a signal when the fluid vaporizes within said throat, and means including pressure responsive means for driving said first fluid circulating means in response to the signal of said last-named means.

5. A heat exchanging system comprising a fluid circulating device adapted to circulate fluid in response to temperature variations, a heat exchanger, means for circulating a fluid through said heat exchanger, said means including a venturi section through which at least a portion of the fluid circulated flows, the fluid circulated through said venturi section and said heat exchanger being adapted to vaporize at the throat of said venturi section at a predetermined temperature, means for generating a signal when the fluid vaporizes within said throat, and means for driving said fluid circulating device in response to the signal of said last-named means.

6. A heat exchanging system comprising a fluid circulating device adapted to circulate fluid in response to temperature variations, a heat exchanger, a pump for circulating a fluid, conduit means interconnecting said pump and said heat exchanger, a venturi section formed in a portion of said conduit means, the fluid circulated by said pump being adapted to vaporize at the throat of said venturi section at a predetermined temperature, means for generating a signal when the fluid vaporizes within said throat, and means for driving said fluid circulating device in response to the signal of said last-named means.

7. A heat exchanging system comprising a first pump adapted to circulate a fluid in response to temperature variations, a second pump for circulating a fluid, a heat exchanger, conduit means interconnecting said pumps and said heat exchanger, a venturi section formed in a portion of said conduit means, the fluid circulated by said pumps being adapted to vaporize at the throat of said venturi section at a predetermined temperature, means for generating a signal when the fluid vaporizes within said throat, and means for driving said first pump in response to the signal of said last-named means.

8. A cooling system for a liquid cooled internal combustion engine comprising a fluid circulating device adapted to be driven in response to temperature variations, a cooling jacket for said engine, a coolant pump for circulating liquid coolant, a radiator for dissipating the heat generated by said engine, conduit means interconnecting said coolant pump, said cooling jacket and said radiator, a venturi section positioned in a portion of said conduit means, the liquid coolant flowing through said venturi section being adapted to vaporize at the throat of said venturi section at a predetermined coolant temperature, means for generating a signal when the coolant vaporizes within said throat, and means for driving said fluid circulating device in response to the signal of said last-named means.

9. A cooling system for a liquid cooled internal combustion engine comprising a cooling jacket for said engine, a first coolant pump for circulating a liquid coolant in response to temperature variations, a second coolant pump driven by said engine for circulating a liquid coolant during operation of said engine, a radiator for dissipating the heat generated by said engine, conduit means interconnecting said coolant pumps, said cooling jacket and said radiator, a venturi section positioned in a portion of said conduit means, the liquid coolant flowing through said venturi section being adapted to vaporize at the throat of said venturi section at a predetermined coolant temperature, means for generating a signal when the liquid coolant vaporizes within said throat, and means

for driving said first coolant pump in response to the signal of said last-named means.

10. A heat exchanging system comprising a fluid circulating device adapted to be driven in response to temperature variations, a heat exchanger, means for circulating a fluid through said heat exchanger, a venturi section positioned to receive at least a portion of the fluid flowing through said heat exchanger, the fluid flowing through said venturi section being adapted to vaporize at the throat of said venturi section at a predetermined temperature, means for sensing the pressure differential caused at said throat by the fluid vaporization, and means including pressure responsive means for driving said fluid circulating device in response to the sensing of a pressure variation by said last-named means.

15. A heat exchanging system comprising a fluid circulating device adapted to be driven in response to temperature variations, a heat exchanger, a pump for circulating a fluid, conduit means interconnecting said pump and said heat exchanger, a venturi section formed in a portion of said conduit means, the fluid circulated through said heat exchanger and said venturi section being adapted to vaporize at the throat of said venturi section at a predetermined temperature, means for sensing the pressure differential caused at said throat by the fluid vaporization, and means including pressure responsive means for driving said fluid circulating device in response to the sensing of a pressure variation by said last-named means.

20. A heat exchanging system comprising a first pump adapted to circulate a fluid in response to temperature variations, a second pump for circulating the fluid, a heat exchanger, conduit means interconnecting said pumps and said heat exchanger, a venturi section formed in a portion of said conduit means, the fluid circulated by said pumps being adapted to vaporize at the throat of said venturi section at a predetermined temperature, means for sensing the pressure differential caused at said throat by the fluid vaporization, and means including pressure responsive means for driving said first pump in response to the sensing of a pressure variation by said last-named means.

25. A cooling system for a liquid cooled internal combustion engine comprising a fluid circulating device, a cooling jacket for said engine, a coolant pump for circulating a liquid coolant, a radiator for dissipating the heat generated by said engine, conduit means interconnecting said coolant pump, said cooling jacket and said radiator, a venturi section positioned in a portion of said conduit means, the liquid coolant flowing through said venturi section being adapted to vaporize at the throat of said venturi section at a predetermined coolant temperature, means for sensing the pressure differential caused at said throat by the coolant vaporization, and means including pressure responsive means for driving said fluid circulating device in response to the sensing of a pressure variation by said last-named means.

30. A cooling system for a liquid cooled internal combustion engine comprising a first coolant pump adapted to be driven by said engine in response to temperature variations, a second coolant pump driven continuously by said engine, a cooling jacket for said engine, a radiator for dissipating the heat generated by said engine, conduit means interconnecting said coolant pumps, said cooling jacket and said radiator, a venturi section positioned in a portion of said conduit means, the liquid coolant flowing through said venturi section being adapted to vaporize at the throat of said venturi section at a predetermined coolant temperature, means for sensing the pressure differential caused at said throat by the coolant vaporization, and means including pressure responsive means for coupling said first coolant pump to said engine in response to the sensing of a pressure variation by said last-named means.

35. A cooling system for a liquid cooled internal combustion engine comprising a cooling jacket for an internal

combustion engine, a first coolant pump adapted to be driven intermediary by said engine, a second coolant pump adapted to be driven continuously by said engine, a radiator for dissipating the heat generated by said engine, conduit means interconnecting said coolant pumps, said cooling jacket and said radiator, and temperature responsive clutch means for coupling said first coolant pump to said engine when the coolant temperature exceeds a predetermined value.

16. A heat exchanging system comprising a pump, a driving member, a heat exchanger, conduit means interconnecting said pump with said heat exchanger, a venturi section, means for circulating a fluid through said venturi section, a fluid pressure responsive clutch for drivingly coupling said pump to said driving member comprising biasing means for urging said clutch to one of its engaged and disengaged positions, fluid pressure means opposing said biasing means and urging said clutch to its other position, and conduit means interconnecting said fluid pressure means with said venturi section at its throat for transmitting the pressure at said throat to said fluid pressure means, the fluid flowing through said venturi section being adapted to vaporize at a predetermined temperature for decreasing the force exerted by said fluid pressure means whereby said biasing means may urge said clutch into the first of said positions.

17. A heat exchanging system comprising a first pump, a second pump, a fluid pressure responsive clutch for drivingly coupling said first pump to said driving member, means coupling said second pump to said driving member, a heat exchanger, conduit means interconnecting said pumps with said heat exchanger, a venturi section positioned in a portion of said conduit means, said fluid pressure responsive clutch comprising biasing means for urging said clutch to one of its engaged and disengaged positions, fluid pressure means opposing said biasing means and urging said clutch to the other of its positions, conduit means interconnecting said fluid pressure means with said venturi section at its throat for transmitting the pressure at said throat to said fluid pressure means, the fluid flowing through said venturi section being adapted to vaporize at a predetermined temperature for decreasing the force exerted by said fluid pressure means whereby said biasing means may urge said clutch into the first of said positions.

18. A cooling system for an internal combustion engine comprising a fluid circulating device, a fluid pressure responsive clutch for drivingly coupling said fluid circulating device to said engine, a coolant pump, means drivingly coupling said coolant pump to said engine, a radiator, a cooling jacket for said engine, conduit means interconnecting said coolant pump, said cooling jacket and said radiator, a venturi section positioned in a por-

tion of said conduit means, said fluid pressure responsive clutch comprising biasing means for urging said clutch to its engaged position, fluid pressure means opposing said biasing means and urging said clutch to its disengaged position, and conduit means interconnecting said fluid pressure means with said venturi section at its throat for transmitting the pressure at said throat to said fluid pressure means, the coolant flowing through said venturi section being adapted to vaporize at a predetermined temperature for decreasing the force exerted by said fluid pressure means whereby said biasing means may urge said clutch into engagement to drive said fluid circulating device.

19. A cooling system for an internal combustion engine comprising a cooling jacket, a first coolant pump, a fluid pressure responsive clutch for drivingly coupling said first coolant pump to said engine, a second coolant pump, means drivingly coupling said second coolant pump to said engine, a radiator for dissipating the heat generated by said engine, conduit means interconnecting said coolant pumps, said cooling jacket and said radiator, a venturi section positioned in a portion of said conduit means, said fluid pressure responsive clutch comprising biasing means for urging said clutch into its engaged position, fluid pressure means opposing said biasing means and urging said clutch into its disengaged position, and conduit means interconnecting said fluid pressure means with said venturi section at its throat for transmitting the pressure at said throat to said fluid pressure means, the coolant flowing through said venturi section being adapted to vaporize at a predetermined temperature for decreasing the force exerted by said fluid pressure means whereby said biasing means may urge said clutch into its engaged position for drivingly coupling said first coolant pump to said engine.

20. A temperature responsive fluid pump comprising a first impeller, a second impeller concentrically disposed with respect to said first impeller and axially aligned therewith, a driving shaft, means for affixing one of said impellers to said driving shaft, fluid pressure responsive clutch means for drivingly coupling the other of said impellers of said driving shaft, said fluid pressure responsive clutch means comprising biasing means for urging said clutch means to one of its engaged and disengaged positions and fluid pressure means for urging said clutch to the other of said positions, a venturi section adapted to receive a portion of the fluid circulated by said impellers, and means for transmitting the pressure at the throat of said venturi section to said pressure responsive means.
